UNITED STATES PATENT OFFICE.

DERWIN W. BOWIE, OF WOODRIDGE, NEW JERSEY, ASSIGNOR TO UNITED SHOE MANUFACTURERY CORPORATION, OF PATERSON, NEW JERSEY, A CORPORATION OF NEW JERSEY.

HEEL-SEAT-FITTING MACHINE.

Original application filed August 24, 1917, Serial No. 188,003. Divided and this application filed July 3, 1922. Serial No. 572,417.

This invention relates to machines for shaping soles to prepare them to receive heels which are to be attached, the present application being a division of my co-pending application No. 188,003, filed Aug. 24, 1917, upon which Letters Patent of the United States, No. 1,432,524, were granted October 17, 1922.

In the manufacture of shoes having leather heels it is customary to attach a rough heel, then to trim the heel and the edge of the heel portion of the sole simultaneously and later to scour and burnish them. With wooden heels, this procedure has not been found to be practicable since to trim a wooden heel and the edge of a leather sole simultaneously in a satisfactory manner is difficult if not impossible. Moreover a wooden heel is commonly covered with a thin veneer of leather which can not be subjected to the scouring operation without injury. Accordingly it is the practice to finish wooden heels completely before they are attached and to trim off the edge of the heel portion of the sole of the shoe so as to permit the upper edge of the heel to extend close to the upper of the shoe.

Each of these wooden heels has a cavity in its upper face; and the trimming of the heel portion of the sole should be such as to provide a seat to receive this cavity. Hitherto this operation has been performed by hand or by machines like that of U. S. Letters Patent No. 1,307,285, granted June 17, 1919, in which the work is held stationary while traveling cutters form the heel-seat, such machines having proved accurate and satisfactory.

A general object of the present invention is to provide a machine of a simpler type for use in fitting heel seats. To this end one feature of the invention comprises relatively transversely movable cutting means and shoe supporting means for forming an abrupt shoulder at the heel breast line of a sole attached to a shoe, or abrupt shoulders at opposite sides of the sole, to abut against the breast end of a heel. These shoulders may be formed on soles which have previously been treated, for example by the means claimed in Letters Patent No. 1,432,524, which were granted on my above-identified application, which forms a horse-shoe shaped bevel on each sole by removing waste stock about the periphery of the heel end, the

bevel and the shoulder or shoulders, taken together, providing a seat for the heel which is to be attached; or the bevel may be formed by the other means, either before or after the formation of the shoulders. I prefer to use a cutter operating transversely of the sole to form the shoulder, as described, and simultaneously to form a beveled section adjoining the shoulder to complete the cut made by the beveling cutter.

In the illustrated embodiment of my invention, power-operated rotary cutting means is provided and a shoe resting on a movable support having a gaging and supporting member entering the rand crease of the shoe is arranged to be moved relatively to the cutting means to form the shoulder or shoulders as described.

These and other features of the invention, including certain details of construction and combinations of parts, will be described as embodied in an illustrative machine and will be pointed out in the appended claims.

Referring now to the accompanying drawings,—

Fig. 1 is an end elevation of a machine in which the present invention is embodied;

Fig. 2 is a front elevation of the machine;

Fig. 3 is a perspective of a portion of a shoe showing the heel-seat which is formed by the beveled cutter; and

Fig. 4 is a similar perspective showing the shoulders on offsets which are formed by the milling cutters.

Rotatably mounted in bearings in the frame of the machine are two shafts 5 and 7, the shaft 5 being driven by a belt 9 and the shaft 7 being driven from the shaft 5 by a belt 11. Fast to the end of the shaft 5 is an end cutter 13, herein shown as of frusto-conical shape, and co-operating with this cutter is a guiding member 17 herein shown as a gage or rest the purpose of which is to facilitate guiding and turning the work while it is moved past the cutter 13. The gage 17 comprises a narrow plate having a beveled lower end adapted to enter the rand crease of a shoe and provided at its upper end with a transverse slot 19 (Fig. 2) to receive a disk 21 carried at the lower end of an adjusting screw 23. A screw bolt 25, which passes through a slot in the gage and is threaded into the arm 27 which carries the thumb screw 23, serves to hold the gage firmly in

adjusted position. The arm 27 is pivoted to the frame of the machine at 29 and is held upright, as shown, by a latch 31, the purpose of this construction being to permit the gage to be swung out of the way in order to facilitate removal and replacement of the cutter 13.

The illustrative machine is designed to operate upon the sole after it has been attached to the shoe; and in the operation of the machine, as thus far described, the rand crease is presented to the gage 17 at one end of the line where the breast of the heel when attached will join the sole. The shoe is the moved along and turned until the opposite end of the line of the heel breast has been reached. During this moving and turning the cutter 13 removes stock in a horseshoe-shaped area from the heel portion of the sole with the result illustrated in Fig. 3. In Fig. 1 one of the positions occupied by the shoe during the cutting operation is indicated in dotted lines. It should be noted that the cut extends from substantially the line of junction of the upper with the sole to a line located a sufficient distance inside said line of junction to provide a beveled seat for the heel which is to be attached.

The above-described trimming mechanism for producing the result illustrated in Fig. 3 is not claimed in the present application, as it forms the subject-matter of the above-identified Patent No. 1,432,524.

When heels of certain styles, such as the Cuban type, are to be attached, it is desirable to produce sharp offsets or shoulders at the ends of the horseshoe-shaped cut to provide abutments against which the upper forward corners of the heel may be placed. To this end there are mounted on the shaft 7, one at each end, milling cutters 33, and adjacent to each milling cutter is a gage or rest 35, constituting a sole supporting and positioning member adapted to enter the rand crease between the upper and the sole to support the marginal part of the sole and present the same obliquely to the cutter. The rotation of the cutters and the arrangement of their teeth is such that the cutting action of each tooth is from the tread face obliquely into the sole, in all positions of the sole with respect to the cutter and from the center of the tread face outwardly toward the periphery, while each cutter, considered as a whole, cuts from the periphery of the sole progressively inwardly toward the middle of the sole. While in the illustrated machine separate milling cutters are provided to form the two shoulders at opposite edges of the sole, a single cutter might be used for cutting both shoulders, or for cutting a single shoulder entirely across the sole, if desired, instead of using two cutters, one for the right and one for the left side as shown.

The gages 35 are vertically adjustable by sole for the attaching of a heel.

means of thumb screws 37 in sockets in the two approximately upright arms of a forked bell crank lever 39 which is pivoted to the frame of the machine at 41 (Fig. 2). Lever 39 is normally held up by a spring 43 but may be pulled down so as to turn it in a counter-clockwise direction, as viewed in Fig. 2, about the pivot 41 by depressing a treadle (not shown) which is attached to the lower end of a treadle rod 45. The clockwise movement of the bell crank lever 39 is limited by contact of the lower arm of the lever with the frame of the machine; and this extreme position is its normal position due to the action of the spring 43. After the seat has been formed as illustrated in Fig. 3, if it is desired to produce the shoulders illustrated in Fig. 4, the shoe is presented, as indicated in dotted lines in Figs. 1 and 2, first to one milling cutter and then to the other, the treadle being manipulated to position the gages so that the tread face of the sole will be presented obliquely to the cutter so that cuts of the desired depth will be made. These cuts will provide not only shoulders or abutment surfaces to co-operate with the breast of the heel but also beveled sole edges constituting heel-supporting surfaces, in planes substantially at right angles to the planes of the shoulders.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:

1. A machine for use in completing a heel seat on a sole previously trimmed by a rotary end cutter to remove a horseshoe-shaped portion of waste from the heel part of the sole, said machine comprising, in combination, two cutters, power-driven means for operating them to form sharp offsets or shoulders at opposite ends of the cut made by said end cutter to complete the removal of waste material to fit the sole for the attaching of a heel, and a gage adjacent to each cutter arranged to position the work so that the cutting is done from the periphery toward the middle portion of the sole.

2. A machine for operating upon a sole previously trimmed to provide a horseshoe-shaped bevel about the margin of its rear end, said machine comprising, in combination, a cutter and a gaging means co-operating with said sole adjustable to vary the depth of the cut made by said cutter, said cutter and gaging means being constructed and arranged for relative movement to form a sharp offset or shoulder in the sole at the end of the horseshoe-shaped bevel to fit the sole for the attaching of a heel.

3. A machine for operating on a sole previously trimmed by removal of a horse-shoe-shaped section of waste from about the margin of its heel end, said machine comprising, in combination, a cutter, a gage adjustable to vary the depth of the cut, and treadle-controlled means for relatively traversing the cutter and gage to form sharp offsets or shoulders at the ends of the trimmed portion of the sole. 10
4. A heel seat fitting machine comprising means for completing the fitting of a sole which is attached to a shoe and which has been trimmed about the periphery of its heel end, said means including a power-operated rotary cutter and shoe supporting and positioning means co-operating therewith to form a sharp shoulder transversely of the sole at the heel breast line. 15
5. A heel seat fitting machine comprising means for completing the fitting of a sole which is attached to a shoe and which has been trimmed about the periphery of its heel end, said means including a cutter, a shoe supporting device, and means for relatively traversing the cutter and said device transversely of the sole of the shoe to form a heel-engaging shoulder at the heel breast line. 20
6. A heel seat fitting machine comprising means for completing the fitting of a sole which is attached to a shoe and which has been trimmed about the periphery of its heel end, said means including a cutter, a shoe supporting device, and means for relatively traversing the cutter and said device transversely of the sole of the shoe to form a heel engaging shoulder at the heel breast line, and means for relatively adjusting said device and said cutter to change the depth of the shoulder formed thereby. 30
7. A machine for fitting the sole of a shoe to receive the cavity in a heel comprising, in combination, a power-operated cutter, shoe positioning means, and a mounting for said cutter and positioning means constructed and arranged for relative traversing movement of the cutter and shoe so that the cutter operates from the edge of the sole of the shoe inwardly to form a sharp shoulder or offset at the heel breast line which terminates before reaching the center of the sole. 40
8. A machine for fitting the sole of a shoe to receive the cavity in a heel comprising, in combination, a power-operated cutter, shoe positioning means, and a mounting for said cutter and positioning means constructed and arranged for relative traversing movement of the cutter and shoe so that the cutter operates transversely of the sole of the shoe to form a sharp shoulder or offset at the heel breast line. 50
9. A device for use in fitting the sole of a shoe comprising, in combination, a power-operated cutter, and a shoe positioning means, said cutter and positioning means being constructed and arranged for relative traversing movement of the cutter and shoe so that the cutter operates from the edge of the sole of the shoe inwardly to form a sharp shoulder or offset at the heel breast line. 60
10. A device for use in fitting the sole of a shoe comprising, in combination, a power-operated cutter, and a shoe positioning means, said cutter and positioning means being constructed and arranged for relative traversing movement of the cutter and shoe transversely of the shoe to form a sharp shoulder or offset at the breast line of the sole of the shoe and a beveled sole edge in a plane substantially at right angles to the plane of the shoulder. 70
11. A device for forming a sharp shoulder on the edge of a sole comprising, in combination, a milling cutter, a shoe positioning device, and a mounting for said device for rocking it toward the edge of the milling cutter, to position a shoe so that the cutter will form a sharp shoulder or offset substantially at right angles to the edge of the sole of the shoe and a beveled sole edge in a plane substantially at right angles to the shoulder. 80
12. A machine of the class described comprising, in combination, a device for operating on a shoe, a pivotally mounted shoe positioning member including a gage seating in the crease between the upper and sole of a shoe, and means for rocking said member to present the sole of the shoe to said device, from the periphery progressively toward the middle of the sole. 90
13. A heel seat fitting machine having, in combination, a cutter operative to make a heel breast receiving cut in the sole of a shoe, a pivotally mounted shoe positioning member including a gage seating in the crease between the upper and sole of the shoe, a spring to rock said member to an inoperative position away from said cutter, and a manually-controlled lever for rocking said member against the tension of the spring to present to said cutter a shoe positioned by the member. 100
14. A machine of the class described comprising, in combination, a milling cutter, a shoe supporting device having a flange to enter the rand crease of a shoe, and means for relatively traversing the milling cutter and said device transversely of the shoe. 110
15. A machine of the class described comprising, in combination, a power rotated cutter, a shoe supporting device adjustable toward and from the cutting plane of the cutter, and means for relatively moving said device and said cutter to form a cut of constantly decreasing depth transversely of the sole of the shoe. 120
16. A machine of the class described having, in combination, a cutter, and a shoe sup- 130

port constructed and arranged to rock about an axis below the cutter in such a manner as to cause the cutter to operate transversely of the sole of the shoe and progressively to decrease the depth of the cut made by the cutter.

17. A machine of the class described comprising, in combination, a rotary shaft and a pair of rotary cutters carried thereby, a support pivotally mounted to rock about an axis parallel to the shaft, and a pair of shoe positioning devices carried by the support, one adjacent each cutter, for use in guiding a shoe thereto.
18. A heel seat fitting machine having a shoe support, a cutter for making in the sole of a shoe upon the support a breast cut against which the breast of a heel is to be placed, and means for causing relative movement of the cutter and the shoe upon the support transversely of the sole of the shoe to cause the cutter to enter the sole from the periphery and to cut toward the middle of the sole.
19. A machine for forming abutments in the soles of shoes comprising a rotatable cutter and a work rest having a sole supporting and positioning member adapted to occupy the crease at the side of the shoe between the outer sole and upper to support the marginal part of the sole and present the same obliquely to said cutter to allow the latter to recess the edge of the sole thereby to form an abutment for co-operation with a heel to be attached to the shoe.
20. A heel seat fitting machine comprising a sole-positioning guide arranged to engage a shoe in the crease between the upper and sole and a shoulder-forming tool having a cutting edge movable obliquely to the heel seat surface and transversely of the sole edge from its outer to its inner side at the rear of the heel breast line to form a shoulder at said line.
21. A heel seat fitting machine comprising a crease guide having surfaces arranged to

engage the inner side of the sole and the adjacent portion of the upper of a shoe and a tool having a cutting edge movable obliquely to the surface of the sole and transversely of its edge, from the outer side thereof to the sole-engaging surface of the guide in all positions of the sole with respect to the cutter as the sole is supported by the guide.

22. A heel seat fitting machine comprising a guide for the heel seat portion of the sole of a shoe and a tool having a cutting edge movable about an axis from the outer side of the shoe sole to said guide and in a direction oblique to the sole surface at the points of engagement therewith to form a shoulder surface and an adjacent heel-supporting surface.

23. A machine for fitting the sole of a shoe to receive the cavity in a heel comprising, in combination, a power-operated cutter, shoe positioning means, a mounting for said cutter and positioning means constructed and arranged for relative traversing movement of the cutter and said shoe positioning means so that the cutter operates transversely of the sole of the shoe to form a sharp shoulder surface at the heel breast line extending inwardly from the exposed surface of the sole, and means adjustable to vary the depth of the cut made in forming said shoulder.

24. A heel seat fitting machine comprising a rotatable cutter and means pivotally supported upon an axis substantially parallel to the axis of the cutter constructed and arranged to support the sole of a shoe so that the heel seat of the sole is presented obliquely to the cutter as said means is oscillated about its pivot to cause the cutter progressively to remove material from the outside of the sole toward the middle of the heel seat.

In testimony whereof I have signed my name to this specification.

DERWIN W. BOWIE.
